PLASTIC SHOE

Mabel P. Riesing, Pontiac, Mich., assignor to
The Firestone Tire & Rubber Company, Akron,
Ohio, a corporation of Ohio

Application February 25, 1943, Serial No. 477,165

2 Claims.

(Cl. 36—25)

The present invention relates to shoes, especially to fancy, or dress shoes or to shoes having attractive and distinctive appearances.

Heretofore substantially all shoes have been made from leather or fabric, but recently the use of plastic material has been introduced in shoe manufacture. Heels of shoes are especially adapted for manufacture from plastic material. However, the present invention contemplates manufacture of an entire shoe from a plastic material.

Many advantages accompany the use of a plastic material in shoe manufacture, among which are that the sole and heel of the shoe can be formed integrally from a solid, or hollow plastic block. Then too, the shoes need not be molded or cast, but can be machined from or cored out of, a solid block of plastic material, when desired. The plastic used in the shoe will not deteriorate on exposure to air or water, as conventional shoe constructions, which characteristic also enables the shoe to be washed off to restore the original luster of the shoe. Use of a transparent or translucent plastic material enables novel color effects to be produced in the shoes by painting the inner surface (when a hollow shoe is made) or an outer surface thereof, with a distinctive type of shoe also being provided when a colored plastic material is used. Forming the high heel of a shoe integrally with the sole portion of the shoe prevents the heel from breaking off the shoe, as in ordinary shoe constructions, so that shoes made in accordance with the invention are safer than standard types of shoes. When the shoes are molded to shape, a metal arch support can be embedded in the shoe as it is formed. Furthermore, the integral formation of the sole and heel of the shoe reduces the expense of construction of the shoe, since the sewing and tacking of soles to the shoe is avoided, as is the nailing on of heels. Insoles for the shoes are readily cemented in place while insoles in conventional shoes usually are either nailed or sewed into the shoe.

The general object of the present invention is to provide an improved, attractive shoe made from plastic material, which shoe is inexpensively constructed and has a long life.

Another object of the invention is to provide a shoe which can be readily cleaned.

A further object of the invention is to provide a safe shoe construction wherein the parts thereof cannot readily be broken therefrom.

A further object of the invention is to provide a shoe which can have a variety of means asso-

ciated therewith for securing it to the wearer's foot.

The foregoing and other objects will be manifest from the following specification, with particular reference to the accompanying drawing, of which:

Figure 1 is a perspective view of a shoe embodying the invention;

Figure 2 is a longitudinal vertical section of the shoe shown in Figure 1;

Figure 3 is a transverse section of the shoe on line 3—3 of Figure 2; and

Figures 4 and 5 are fragmentary sectional views of joints which may be used in securing parts of the shoe together.

Referring to the drawing, a shoe 10 is shown, which shoe is made solely from a plastic material and which has a distinctive and attractive appearance. Any suitable plastic, or moldable material may be used in the practice of the invention, for example, cellulose acetate or methyl methacrylate. As indicated above, the shoe and/or parts thereof can be initially molded to the desired form, or they can be machined out of a solid block of plastic material. The shoe 10 includes an upper or a top member 11, which is supported by a base member 12, and the upper member 11 has an upper surface 11a which is adapted to engage with and support a person's foot, there being a heel engaging portion 11b formed at the rear end of this member. The under side of the top member 11 is cored out or recessed or hollow to reduce the weight and volume of plastic material used in forming the same. It will be seen that the top side of the base member 12 is cored out or removed in the same manner whereby the base member is substantially U-shaped in transverse section. Two ribs 13 are formed in the outer surface of the base member 12 and extend around the periphery thereof. The lower edge of the top member 11 telescopes over the upper margin of the member 12 and engages with the upper rib thereon so as to be supported thereby. By arranging the cored out sides of the members 11 and 12 in confronting relation, the shoe 10, which is hollow, is formed. The juncture of the members 11 and 12 is a substantially horizontal plane, which plane is substantially parallel to the bottom of the shoe. After the member 11 is positioned on the member 12, it may be cemented or otherwise secured in position.

Straps or ribbons 14 are carried by the shoe to secure the shoe to the wearer's foot. These straps 14 may be nailed or cemented to the upper

portion of the upper member of the shoe. However, slots 15 are shown extending through the members forming the shoe whereby the straps 14 can be threaded through the slots and formed into loops through which the wearer's foot is inserted. This arrangement facilitates changing the straps 14 so that the appearance of the shoe can be changed by substituting various colored straps 14 for each other, whereby the straps could be changed to match the dress of the person wearing the shoe.

Figure 4 shows adjacent edge portions of two members used in forming a hollow shoe. In this instance a member 21 is provided with a protruding shoulder 22 on one of its surfaces adjacent its lower margin and this shoulder engages with the margin of a substantially L-shaped projection 23 formed on the upper edge of a second shoe member 24 whereby a strong connection is formed between the component parts of the shoe. Figure 5 shows a lapped-butt joint which can be formed between two shoe sections. A recess 25 is formed in one side of the lower edge of a shoe member 26 whereas a similar recess 27 is formed in the opposite side of the upper edge of a second shoe member 28, which recesses are adapted to receive the adjacent marginal portion of the opposite shoe member, whereby a smooth joint is formed between the two and these shoe parts can be permanently united by cementing or nailing the overlapped portions of the shoe sections together.

From the foregoing, it will be apparent that a sturdy shoe of unusual construction and ap-

pearance is provided by the invention. This shoe is easily manufactured and retains its original shape throughout its life. The shoe is made from two parts which are hollowed or cored out, or solid, as desired. The shoe is readily cleaned, and possesses the other features mentioned hereinbefore, whereby the objects of the invention are achieved.

It will be appreciated that the foregoing illustration and description of the invention is for illustrative purposes only and that the spirit of the invention includes modifications thereof such as come within the scope of the appended claims.

I claim:

- 15 1. A shoe comprising a molded foot supporting structure having a reversely curved foot-conforming top face and a substantially flat ground-engaging bottom face, said structure consisting of a bottom section, and an upper section superposed thereon and permanently attached thereto, the juncture of said sections lying in a plane that is substantially parallel to the flat bottom face of the structure.
- 20 2. A shoe comprising a hollow foot supporting structure having a reversely curved foot-conforming top face and a substantially flat ground-engaging bottom face, said structure consisting of a bottom section and an upper section superposed thereon, the confronting sides of said sections being recessed, said sections being permanently attached to each other, the line of juncture being in a plane that is substantially parallel to the flat bottom face of the structure.

MABEL P. RIESING.
